UNITED STATES PATENT OFFICE.

AUGUST LINDE, OF MUCKENBERG, GERMANY.

INSULATOR FOR THE SUSPENSION OF LIVE CABLES FOR ELECTRIC RAILWAYS.

Application filed November 6, 1924. Serial No. 748,087.

To all whom it may concern:

Be it known that I, AUGUST LINDE, a citizen of the Republic of Germany, residing at Muckenberg, Nieder-Lausitz, Kreis Liebenwerda, Germany, have invented certain new and useful Improvements in Insulators for the Suspension of Live Cables for Electric Railways, of which the following is a specification.

10 In the known arrangements for the suspension of the live cable for electric trams or railways, which consist of an iron casing insulator comprising a porcelain insulating member and a bolt for holding the cable, these parts are either cemented or plastered together and this leads to unsatisfactory conditions, as cement and plaster are unstable when exposed to vibrations and the influence of the weather and line breakages 20 can easily take place with all their serious consequences. Consequently the parts of the insulator are not interchangeable, or only with difficulty, and this is a defect in view 25 of the necessity of keeping them in good condition.

Now the form of insulator according to this invention eliminates all these disadvantages. The invention consists in the fact that in assembling the insulating member 30 and its casing no cementing or plastering is employed but these parts grip one on the other by means of ridges and grooves or a bead and corresponding groove, or both, and the casing is formed in two parts adapted to be bolted together whereby the insulator can be clamped fast and easily exchanged. The bolt for fastening the live cable passes right through the insulator, rests with its head in a depression therein, which is closed by 40 means of a porcelain plate, or else the insulator is entirely closed at the top and a bolt with an elliptical head is inserted into a recess in the insulating member and turned within this recess, the bottom of the recess 45 being enlarged for this purpose.

The insulator of this invention is shown in the accompanying drawings in which:—

50 Figure 1 is a front elevation of the insulator.

Figure 2 a lateral elevation of the same, with one part of the casing removed.

Figure 3 is a lateral elevation of same with a modified form of cable carrying bolt.

55 Figure 4 is a cross section on line A—B of Figure 1.

Figure 5 is a cross section on line C—D of Figure 3.

Figure 6 is a plan view of the insulator shown in Figure 3, and

Figures 7 and 8 show two other forms of attachment for the casing and with a part thereof removed.

The insulator *a* is massively constructed and at the bottom projects considerably from its setting, so as to withstand all 60 stresses and prevent interruptions in the current supply. It is mounted in an iron casing *b*, *c* which, in order to afford protection against rain, is provided at the top with a rooflike overhanging plate *d*, which towards 70 the top is fashioned as a closed ring *f* provided with an adjustment screw *e* (Figures 1—3), or as a plate *g* (Figure 7), or otherwise according to the type of suspension attachment, or finally it can be provided also 75 with a winged structure *h* as shown in Figure 8.

One half *b* of the casing *b*, *c* is firmly connected with the plate *d*, while the other half *c* is connected by means of lugs and studs *k* 80 with the part *b* and can be removed when it is desired to test or exchange the insulator *a*. In order that the insulator *a* may not be loosened from its casing *b*, *c* when subjected to a strong pull or pressure, it is gripped by 85 means of ridges *l* or the bead *l'* or both, the casing *b*, *c* being provided with corresponding depressions *l*², *l*³ (Figure 8). Cementing or plastering is entirely obviated with this method of attachment. The porcelain insulator *a* lies directly upon its iron casing *b*, *c* and can, after loosening a stud *k*, be turned 90 therein. The underneath part *q* of the insulator *a* is concave so as to keep water away. 95

The bolt *m* passes loosely through the aperture *m'*, fits deeply with its head *n* into an hexagonal recess *n'* in the insulator *a*, and is screwed tightly on to the insulator by means of a nut *o*. The bolt *m* projects so 100 far as to enable a travelling wire clip to be fastened to it, or it is provided with a further nut (Figure 8) in order that the device may serve as an insulator support. At the top above the head *n* of the bolt *m* a porcelain plate *p* (Figure 2) is inserted into a 105 corresponding recess *p'* in the insulator *a*, the plate *p* having formed integral therewith or suitably secured thereto, a hexagonal attachment *r*, adapted to project into the 110

correspondingly shaped recess n' (Figure 2). From this construction, it will be clear that no cement is required to retain the bolt m in the insulator a . Moreover, leakage of current to the suspending or supporting means will be effectively eliminated.

Instead of the bolt m use can also be made of a readily interchangeable bolt s (Figures 3 to 5), completely insulated at the top by 10 means of the part t of the modified form of insulator a' , whereby the insulation is improved and simplified. The bolt s has an oval preferably ellipsoidal head u , only projecting at two opposite sides, which is inserted from below through an oval aperture u' (Figure 6) in the insulator a' (Figure 6) until it is in the space v , whereupon the bolt is turned through an angle of 90 degrees and the head u lies in the bearing w . This bolt 20 s, u can be exchanged without removing the insulator a' from its casing, as moreover it is neither cemented nor plastered in position.

What I claim and desire to secure by Letters Patent of the United States, is:—

25 1. An insulator for the suspension of live cables, comprising a two part casing, means for detachably securing the parts of the casing together, an insulating member mounted within said casing, groove and ridge connections between the casing and insulating member to retain the insulating member within the casing, the said insulating member being provided with a central longitudinal bore and a countersunk recess 30 in the end of the insulating member concentric with said bore, a cable carrying bolt mounted within the bore, means for closing one end of said casing, and an insulating member interposed between the bolt and the 40 closing means and seated within the countersunk recess.

2. An insulator for the suspension of live cables, comprising a two part casing, means for detachably securing the parts of said 45 casing together, a cover for one end of said casing, an insulating member mounted within said casing, a cable carrying bolt passing through said insulating member and projecting beyond one end thereof, the end 50 of the insulating member adjacent the casing cover being provided with a countersunk portion, and an insulating member between the said bolt and the cover adapted to seat within the countersunk portion of the insulator.

60 3. An insulator for suspending live electric cables, comprising a two part casing, means for detachably securing said parts together, a cover for one end of said casing, an insulating member mounted within said casing, ridge and groove connections between the casing and insulating member to prevent relative longitudinal movement

therebetween, the insulating member being provided with a countersunk portion in the 65 end thereof adjacent the cover, and a central reduced bore communicating with the said countersunk portion, a cable carrying bolt passing through said bore and projecting beyond the end of the insulating member remote from the cover, means for retaining the bolt within the bore, and an insulating member between the bolt and the casing cover seated within the countersunk portion.

4. An insulator for the suspension of live 75 cables, comprising a two part casing, means for detachably securing the parts of the casing together, a cover for one end of said casing secured to one of said parts, means on said cover for supporting the insulator, an 80 insulating member mounted within said casing, connections between the casing and insulating member for retaining the insulating member within the casing, the said insulating member being provided with a recess in the end adjacent said cover, and a bore connecting said recess with the other end of the insulating member, the said bore being of smaller diameter than the recess, a cable carrying bolt mounted within said 85 bore, and an insulating plate between the bolt and the cover of the casing adapted to sit within the recess.

5. An insulator for suspending live electric cables, comprising a two part casing, 90 means for detachably securing said parts together, a cover for closing one end of said casing secured to one of said parts, means on said cover for attaching the insulator to a support, an insulating member mounted 100 within said casing, connections between said insulating member and the casing to retain the insulating member within said casing, the said insulating member being provided in the end adjacent the cover with an enlarged recess and a restricted recess communicating with said first mentioned recess, and a central longitudinal bore between said second named recess and the other end of the insulating member, a cable carrying bolt 110 adapted to fit within said bore, an enlarged head on said bolt adapted to sit within the second named recess, a nut on the outer end of said bolt, and an insulating plate between the head of said bolt and the cover of the 115 casing, the said insulating plate comprising an enlarged portion adapted to sit within the first named recess and a restricted portion adapted to project into the second named recess.

In testimony whereof I affix my signature in presence of two witnesses.

AUGUST LINDE.
